UNITED STATES PATENT OFFICE

GUNNAR C. ENGSTRAND, OF BROOKLYN, NEW YORK, ASSIGNOR TO SALVAGE PROCESS CORPORATION, OF NEW YORK, N. Y., A CORPORATION OF NEW YORK

OIL-PUMPING APPARATUS

Application filed February 18, 1927. Serial No. 169,205.

My invention relates to an apparatus and method for the pumping of heavy viscous material and its transfer to any convenient place of disposal.

Such material cannot be transferred through a hose or pipe line in a solid column, but has to be broken up into fragments which are carried in an air stream set up in the transmission line.

My invention has for its object to provide a combined vacuum pump and air compressor which alternately creates a vacuum and compression in a certain part of the transmission line, the ends of which part are provided with check valves so set that a continuous air stream is created in both the discharge line and suction line.

My invention has also for its object to make the vacuum and compression part vertical with the suction end at top and discharge end at bottom. Also by making the said part double and of a certain length and employing pressure regulating valves in the air pump connections it is possible to place the intakes of the air pump at the lower end of said part and close the intakes before the material will reach them and the pump compression lines will open and expel the material from said part before the pump intakes open again.

The whole operation will thus be continuous and the material will at no time be given the chance to settle and cling to the pipe lines.

In the drawing:—

Figure 1 shows a plan view of the pumping arrangement.

Figure 2 shows an elevation of the double vacuum and compression part of the transmission line and also in a diagrammatic manner the air pump connections thereto.

Figure 3 shows the detail of construction of the intake end of the transmission line.

Referring to the drawing in which like reference characters designate corresponding parts, 1 represents the air pump which is provided with the belt driven fly wheel 2 which drives the pistons back and forth in the vacuum cylinder 3 and in the pressure cylinder 4 by means of a conventional crank arrangement.

The vacuum cylinder is provided with the

air check valves 5 which open to the atmosphere. The pressure cylinder is provided with the air intake valves 6.

Each end of the vacuum cylinder 3 is provided with an intake line 7 which terminates at the lower part of the branches of the vertical part 8 of the transmission line.

Each end of the pressure cylinder 4 is similarly provided with a discharge line 9 terminating at the upper part of said branches.

The lines 7 are provided with pressure regulating valves 10 which preferably are of the spring diaphragm type and so connected that pressure in the pressure cylinder will cause them to close.

The lines 9 are also provided with pressure regulating valves 11 which open at pressure in the pressure cylinder.

The two branches of part 8 are provided with check valves 12 which open in the direction of flow in the transmission line. The branches of part 8 join together at the top with the suction line 13 and at the bottom with the discharge line 14.

Figure 2 shows how the pumped material is sucked into one branch of part 8 while it is being pushed out from the other.

Figure 3 shows the construction of the suction intake of the suction line 13. The intake has an intake nozzle 16 of a reduced diameter and the nozzle is surrounded by holes 17 through which atmospheric air is allowed to enter into the transmission line.

The operation is as follows:—

The air pump 1 is started and the nozzle 16 is inserted in the material to be pumped whereupon the material is sucked up through the nozzle into the suction line 13.

In the meantime the vacuum in the suction line will cause the atmospheric air to rush through the holes 17 with so great a velocity that the viscous material is torn into fragments which are carried along by the attenuated air stream which is created in the suction line.

Consider the moment of the pumping operation illustrated in the drawing. At this moment the fragment laden air is sucked by the air pump through the suction line and down through the leg of the part 8 and the

check valves 12 do automatically take the position illustrated in the drawing at the start of the stroke.

It is to be noted that the pressure cylinder end which is connected to the respective regulating valves 10 is still sucking in atmospheric air but with the piston motion reversed a pressure will build up at this end and the respective regulating valve 10 will 10 close and the attenuated air in the suction cylinder will be compressed and discharged through the valve 5.

The regulating valve 11 in the pump discharge on the other hand will open at pressure and an air blast will emit from the pressure cylinder expelling the fragment laden air from this branch of part 8 and also reversing the position of the check valves 12.

It is to be noted that the duplex branch 20 arrangement renders the transmission continuous in the suction line as well as in the discharge line.

By properly adjusting the length of the vertical part 8 it is possible to cause the pump 25 intake to close before the material reaches the intake, and the air blast from the pressure cylinder will expel the material from the part 8 before the pump intake is again opened and the operation repeated.

30 It is to be noted that the material is in a continuous motion during its entire travel through the transmission line which is of the utmost importance when heavy viscous material is being pumped.

35 If by chance the material should settle on the inside of the transmission line it will most tenaciously cling thereto and interfere with the air flow and soon entirely stop the pumping operation.

40 The arrangement of the pump connections causes the air to move at all times in the same direction as the flow and no interfering air currents will arise.

I do not wish to be understood as limiting 45 myself to the specific details of construction as it is manifest that variations and modifications may be made in the adaptation of the device to various conditions without departing from the spirit and scope of my invention.

50 I claim:—

1. An air transmission comprising in combination a suction line, a pressure line, an intermediate part joining said lines together 55 provided with check valves, an air pump and double suction and discharge connections to said intermediate part, and pressure regulated valves in said connections set to open or close at each pump stroke.

60 2. In an air transmission, a suction line and a pressure line joined together by a double branched vertical part provided with check valves at the ends of the branches, an air pump, double suction and pressure connections from the air pump to each of the

branches provided with pressure regulated valves set to open or close at each stroke of the pump and so connected that the suction will close before the pumped material reaches it and the subsequent air blast will clear the branch before the suction is reestablished. 70

3. An air transmission, comprising a suction line and a pressure line joined together by a double branched part provided with check valves at the ends of the branches, a vacuum cylinder having valves at its ends opening outwardly, a pressure cylinder having valves at its ends opening inwardly, oppositely movable pistons in the cylinders, means for simultaneously operating said pistons, a pair of pipes connecting the ends of the vacuum cylinder to said branches, and a pair of pipes connecting the opposite ends of the pressure cylinder to said branches. 75 80

4. In an air transmission as claimed in 85 claim 3, pressure regulated valves for the first mentioned pair of pipes, and passageways placing said valves in communication with the second mentioned pair of pipes.
